A. C. HAYDEN

MAT

Filed Oct. 31, 1921

Inventor

Arthur C. Hayden
By Harry T. Williams
Atty.

UNITED STATES PATENT OFFICE.

ARTHUR C. HAYDEN, OF BROCKTON, MASSACHUSETTS.

MAT.

Application filed October 31, 1921. Serial No. 511,799.

To all whom it may concern:

Be it known that I, ARTHUR C. HAYDEN, a citizen of the United States, residing at Brockton, in the county of Plymouth and 5 State of Massachusetts, have invented an Improvement in Mats, of which the following description, in connection with the accompanying drawings, is a specification, like characters on the drawings representing 10 like parts.

The invention to be hereinafter described relates to mats for doorways, corridors, passageways and other uses.

A good form of mat for these purposes 15 may comprise laminated blocks or elements of leather or other suitable material which may be strung on rods or strong wires, desirably with a disposition such that the blocks or elements present a checkerwork 20 appearance.

In use it has been found that persons approaching a mat are sometimes liable to strike or catch their feet against the edge of the mat and cause the margin thereof to 25 curl or bend up somewhat away from the floor. As a consequence, persons are liable to trip against the edge of the mat and receive serious injury.

The aim and purpose of the present invention, therefore, is to provide simple and 30 efficient means to prevent the edge of the mat from bending or curling up from such cause.

The character of the invention may be 35 best understood by reference to the following description of one good form thereof shown in the accompanying drawing, wherein:

Fig. 1 is a plan of a portion of a mat embodying the invention;

Fig. 2 is a vertical section through a portion of the mat taken on line 2—2 of Fig. 1;

Fig. 3 is an edge elevation of a portion of the mat;

Fig. 4 is a detail of one of the edge tread devices, certain parts being broken away to disclose structure beyond the same;

Fig. 5 is a detail of one of the leather pieces used in the formation of one of the 50 blocks or links;

Fig. 6 is a perspective view of one of the pivoted tread members; and

Fig. 7 is a perspective view of the attaching element to which the tread member 55 is pivoted.

Referring to the drawing, the mat shown

therein as one good form of the invention, comprises an assembly of links or blocks 1 which may be formed of leather or other appropriate material. In the present instance, these blocks have a laminated character, and each comprises four leather pieces 3 (Fig. 5) which may be conveniently died out of sole leather. It will be understood that the number of these layers or pieces 65 may be varied as desired.

Suitable means may be provided for securing the links or blocks in assembled relation. This means, in the present instance of the invention, comprises rods or 70 strong wires 5 which are entered through registering holes in the blocks. These rods may be bent to present loops 7 at one edge of the mat, and the terminals 9 of the rods may be turned inward and secured by split 75 sleeves 11. The blocks may be so assembled and strung on the rods so as to present a checkerwork appearance. The spaces between blocks at opposite ends of the mat may be filled by smaller blocks 13 which 80 are also strung on the rods.

The thickness of the mat is such that ledges or shoulders of substantial depth occur at the edges of the mat. As stated, persons approaching the mat are liable to 85 kick or strike these edges and cause the same to bend or curl up, with consequent liability of serious injury. This is especially true of the edges of the mat which are perpendicular to the length of the rods. 90

It is desirable, therefore, to provide means to prevent pedestrians from kicking or striking these edges of the mat. This means, in the present instance of the invention, comprises rows or series of tread 95 devices which may extend along opposed ends of the mat.

Each of these devices may include an attaching element which may be conveniently died out of sheet material, and present a 100 tongue 15 (Figs. 2, 4 and 7) adapted to be inserted between the loops of the rods and the blocks adjacent thereto. The tongue may have spurs 17 which may be bent outward and have interlocking engagement with 105 sides of the loops of the rods, the construction being such that the tongue may be securely connected to the edge of the mat.

Projecting from the tongue is a reverse bend 19 carrying a body 21 formed to present hinge lugs 23 at opposite ends thereof. Projecting from the body intermediate the 110

lugs 23 is a stop conveniently in the form of a tab 25 which may be bent downward somewhat from the plane of the body, as will be noted in Figs. 2 and 7. The angle 5 of this tab may be varied by bending the same with respect to the body as desired.

A tread member 27 (Figs. 1, 2 and 6) may be conveniently die cut out of sheet material, and present an inclined tread surface 10 29 which may be strengthened or stiffened by end wings 31.

Eyes 33 may be formed in these wings, and be adapted to receive the hinge lugs 23 referred to. Preferably these eyes are offset 15 a substantial distance from the upper edge of the tread member, so that the upper marginal portion of the tread surface of said member may overlap the body 21 of the attaching element, substantially as shown in 20 Fig. 2.

The construction is such that the tread members are so pivotally connected to the attaching elements, that the tread members may rock or gravitate downward on the pivotal lugs 23, so that the lower edges of the tread members will rest upon and be supported by the floor, as will be noted in Fig. 2.

These tread members, therefore, will always incline from the floor upward toward 30 and substantially to the level of the upper surface of the mat, so that when a person is approaching the mat, if his foot is not lifted a sufficient height to clear the edge of the mat, it will strike against the inclined tread 35 member or members, and be deflected thereby upward to the surface of the mat. As a consequence, it is impossible for the pedestrian to bring his foot into such contact with the mat as will be liable to cause the marginal portion thereof to bend or curl upward.

It is desirable to provide means to limit downward rocking movement of the inclined tread members, so that when the mat is 45 placed on the floor, they cannot turn inward or outward to positions in which they would be inoperative for the purposes described. The stop tabs 25 referred to, lend themselves advantageously for this purpose, and may 50 be adjusted to limit the downward rocking of the tread members as required.

The upward rocking movement of the inclined tread members may also be limited, and this is accomplished, in the present instance, by engagement of the upper marginal portions of the tread members with the bodies of the attaching elements.

If for any reason the marginal portion of the mat should become bent or curled upward to a position, such, for example, as shown in Fig. 3, the inclined pivoted tread members will rock downward, so that their lower edges will remain in engagement with the floor. As a result, these lower edges will 65 never be spaced from the floor, and it will

be impossible for the foot of the pedestrian to catch underneath the inclined tread members and kick up the margin of the mat. When the pedestrian steps on the margin of the mat, his weight will tend to restore the 70 mat to its flat condition, and therefore, in use, the tendency is always to maintain the mat in flat instead of distorted condition.

After the mat has been in use, it may be desirable to reverse the same, thereby making 75 it necessary to reverse the inclined tread devices which may be readily removed by bending the spurs 17 of the attaching elements inward. Then the tread devices may be reversed and secured as before.

It will be understood that the invention is not limited to the specific embodiment shown, and that various deviations may be made therefrom without departing from the spirit and scope of the appended claims. 85

What is claimed is:—

1. A mat comprising a checkerwork formed of blocks, rods inserted through said blocks and having loops at an edge of the mat, attaching elements secured to said loops and having hinge lugs projecting therefrom, and inclined tread members having wings with eyes receiving said lugs, that the tread members may rock on said hinge lugs down into engagement with the floor. 95

2. A mat comprising a checkerwork formed of leather blocks, wire links having legs inserted through the leather blocks to hold them in assembled relation, attaching elements having tongues embraced and held by ends of said links at an edge of the mat, and inclined tread members pivotally connected to said attaching elements and adapted freely to rock down relatively to said attaching elements until the inclined tread 100 members engage the surface on which the mat is placed.

3. A mat comprising a checkerwork formed of leather blocks, wire links having legs inserted through the leather blocks to hold them in assembled relation, attaching elements having tongues embraced and held by ends of said links at an edge of the mat, and inclined tread members pivotally connected to said attaching elements and adapted freely to rock down relatively to said attaching elements until the inclined tread 110 members engage the surface on which the mat is placed, said attaching elements and inclined tread members having parts arranged for engagement to limit downward rocking movement of the inclined members when the marginal portion of the mat to which the inclined members are attached is raised a predetermined distance from the 115 surface on which the mat is placed.

In testimony whereof, I have signed my name to this specification.

ARTHUR C. HAYDEN.
